G. E. WOOD & E. C. MEIER.
TOOL FOR UPSETTING AND CALKING STAY BOLTS.
APPLICATION FILED APR. 7, 1909.

968,625.

Patented Aug. 30, 1910.

UNITED STATES PATENT OFFICE

GEORGE E. WOOD AND EDWARD C. MEIER, OF PHOENIXVILLE, PENNSYLVANIA, ASSIGNEES TO HEINE SAFETY BOILER COMPANY, OF ST. LOUIS, MISSOURI, A CORPORATION OF MISSOURI.

TOOL FOR UPSETTING AND CALKING STAY-BOLTS.

968,625.

Specification of Letters Patent. Patented Aug. 30, 1910.

Application filed April 7, 1909. Serial No. 488,536.

To all whom it may concern:

Be it known that we, GEORGE E. WOOD and EDWARD C. MEIER, both citizens of the United States, residing at Phoenixville, 5 Chester county, Pennsylvania, have invented a certain new and useful Improvement in Tools for Upsetting and Calking Stay-Bolts, of which the following is a full, clear, and exact description, such as will 10 enable others skilled in the art to which it appertains to make and use the same.

This invention relates to tools for upsetting and calking hollow stay-bolts.

Prior to our invention the method practiced in upsetting and calking hollow stay-bolts was as follows:—A tapered drift pin was first driven into the end of the hollow bolt, and the end of the bolt was then upset or mashed down by means of a hammer held 15 in the hand of the operator. Thereafter, the operator took a hammer and chisel or a sharp-pointed tool and calked the head of the bolt or forced its peripheral edge into intimate engagement with the plate through 20 which the bolt extended so as to make a tight joint. This method of upsetting and calking hollow stay-bolts is slow and therefore expensive because it requires three separate steps or operations. First, driving the 25 drift pin into the bolt; second, mashing down or upsetting the end of the bolt with a hand-operated hammer; and third, calking the head of the bolt with a hand-chisel and hammer. Such a method also very 30 often produced an imperfect piece of work for the head of the bolt was not smooth and uniform, the head was very often cut too deeply into the plate, and the bolt very often closed up slightly during the upsetting 35 operation so that it was necessary to ream out the bolt.

The main object of our invention is to provide a tool that will rivet or upset a hollow stay-bolt quickly and also calk it in 40 one operation.

Another object is to provide a stay-bolt upsetting and calking tool that can be connected to a power-operated hammer and which will form a smooth and perfect head 45 on the bolt having its peripheral edge portion sunk or cut into the plate evenly.

Figure 1 of the drawing is a vertical sectional view showing our improved tool in operative position on a hollow stay-bolt, 50 preparatory to the upsetting and calking

operation; Fig. 2 is a vertical sectional view of the bolt, during the first stage of the upsetting operation, namely, after the end of the bolt has been mashed down; Fig. 2^a is a vertical sectional view of the bolt after the 60 upsetting and calking operation has been completed; Fig. 3 is an end view of the tool that upsets and calks the bolt; and Fig. 4 is a top plan view of the anvil or support upon which one end of the bolt rests during the 65 operation of upsetting and calking the opposite end of the bolt.

Referring to the drawing which illustrates the preferred form of our invention, 1 designates a hollow stay-bolt that is 70 screwed into a pair of plates 2 spaced away from each other, and A designates a tool that is used for upsetting and calking the ends of the bolt 1. This tool comprises a shank 3 having a hexagonal-shaped extension 4 which is adapted to be connected to a power-operated hammer 5, shown in dotted lines in Fig. 1, such, for example, as a pneumatic, electric or a hydraulic hammer. The shank 3 of said tool is provided with a 75 head 6 having a tapered center pin 7 that projects into the end of the bolt 1, as shown in Fig. 1, so as to prevent said bolt from closing up during the operation of upsetting the end of the bolt to form a head 80 thereon. The head of the tool is also provided with a plurality of lugs or portions 8 having substantially concaved faces 9 that terminate in calking edges 10, as shown clearly in Fig. 1. 90

While we have herein shown the tool as being provided with three lugs 8 we wish it to be understood that it is immaterial, so far as our broad idea is concerned, how many of such lugs the head 6 of the tool is provided with for our broad idea consists in a tool that has a central pin which is adapted to project into the end of the hollow bolt, a substantially concaved surface for upsetting the end of the bolt to form a solid 100 head thereon, and a calking edge for sinking the peripheral edge of the bolt-head into the plate or member through which the bolt projects. During the operation of upsetting and calking the bolt, the lower end of 105 the bolt rests upon or is supported by an anvil B having a tapered central pin 11 that projects into the lower end of the bolt and a concaved surface 12 that merges into said central pin 11. 110

To upset and calk a hollow stay-bolt with a tool of the construction above described the bolt is placed upon the anvil B, as shown in Fig. 1, the central pin 11 of said anvil projecting into the lower end of the bolt. The tool A, which has been previously connected to some suitable kind of power-operated hammer, is then placed upon the upper end of the bolt so that the central pin 7 on the head of said tool projects into the upper end of the bolt. The power which actuates the hammer is then turned on, and the blows which the hammer imparts to the shank of said tool A cause the substantially concaved surfaces 9 on the head of said tool to upset or mash down the upper end of the bolt, as shown in Fig. 2, the hammer to which the tool is connected being revolved during the upsetting operation so that the concaved surfaces 9 will travel around the end of the bolt and thus gradually mash down the metal and force it laterally over the plate through which the bolt projects. During the last stage of the upsetting operation the power-operated hammer is rocked slightly so as to cause the concaved surfaces 9 on the lugs 8 to round off the upset portion of the bolt and thus form a solid rounded head and after the head has been formed the hammer 5 is canted slightly so as to cause the calking edges 10 on the lugs 8 of the tool to sink the peripheral edge of the bolt-head into the plate 2, as shown in Fig. 2^a, and thus calk said head or form a tight joint between same and the plate 2.

Owing to the fact that the anvil B is provided with an approximately concaved surface 12 the lower end of the bolt will be flanged or upset slightly at 12^a, as shown in Figs. 2 and 2^a, during the operation of upsetting and calking the upper end of the bolt. After the upper end of the bolt has been upset and calked, the plates 2 through which the bolt projects, are inverted so that the upset end of the bolt will rest upon the anvil or supporting member while the opposite end of the bolt is being upset and calked. Preferably, an anvil having a concaved surface that conforms accurately to the head of the bolt is used for supporting the upset end of the bolt while the opposite end of the bolt is being upset and calked but as said anvil is of the same construction as the anvil B shown in Fig. 1, we have not illustrated it, the only difference being in the curvature of the top face of the anvil.

The main advantage of a tool of this construction is that it upsets and calks a stay-bolt in practically a single operation, thus

greatly reducing the time and also the cost 60 of driving hollow stay-bolts. Furthermore, a tool of this construction produces a more finished piece of work for the end of the bolt is subjected to uniform pressure so that a perfectly smooth head will be produced. 65 The head is also calked more perfectly than a bolt calked by a hand-chisel and hammer for the peripheral edge of the bolt-head is sunk uniformly into the plate with which it contacts. 70

While we have herein shown our improved tool used for upsetting and calking a hollow stay-bolt that is screwed into the plates, it will, of course, be obvious that it could be used for upsetting and calking a tube that 75 is merely slipped through openings in the plates and therefore the term "hollow stay-bolt" used in the claims should be construed as covering tubes or unthreaded devices. 80

Having thus described our invention, what we claim as new and desire to secure by Letters Patent is:

1. A tool for upsetting and calking hollow stay-bolts, comprising a shank that is adapted to be connected to a power-operated hammer, a head on said shank provided with means for upsetting or mashing down the end of the bolt so as to form a solid head 95 thereon, a guide on said tool head that projects into the end of the bolt so as to cause the metal in the bolt to be forced laterally during the upsetting operation, and means on said tool head for sinking the peripheral edge of the head on the bolt into the plate 90 or member through which the bolt passes. 95

2. A tool for upsetting and calking hollow stay-bolts, comprising a shank that is adapted to be connected to a power-operated hammer, a head on said shank provided with a tapered guide that is adapted to project into the end of the bolt, lugs on said head provided with curved surfaces that cause the end of the bolt to be upset or mashed down so as to form a solid head on the bolt, 100 and sharp edges on said lugs that sink the peripheral edge of the bolt-head into the plate or member through which the bolt passes. 105

In testimony whereof, we hereunto affix 110 our signatures, in the presence of two witnesses, this 2nd day of April, 1909.

GEORGE E. WOOD.
EDW. C. MEIER.
